UNITED STATES PATENT OFFICE.

NATHAN KOBRE, OF BROOKLYN, NEW YORK.

COLLAR.

Application filed August 30, 1921. Serial No. 496,901.

To all whom it may concern:

Be it known that I, NATHAN KOBRE, a citizen of the United States, residing at Brooklyn, in the county of Kings and State of New York, have invented certain new and useful Improvements in Collars; and I do hereby declare the following to be a full, clear, and exact description of the invention, such as will enable others skilled in the art 10 to which it appertains to make and use the same.

This invention relates to new and useful improvements in collars and more particularly to the soft fold type, the main object 15 of the present invention being the provision of stiffening means for this type of collar which will tend to retain the collar in its proper shape when used by the wearer so as not to become wrinkled and folded into an 20 unsightly condition. Another object of the present invention is the provision of a soft fold collar wherein the stiffening means which tends to hold the collar in an upright position, is incorporated and made a part of 25 the collar itself so as to reduce the expense of causing additional members to be applied to the collar during the construction of the same and thus reduce the cost of making the collar to a minimum.

30 With the above and other objects in view this invention consists in the novel features of construction, combination and arrangement of parts hereinafter more fully set forth, pointed out in the claims and shown 35 in the accompanying drawings in which:

Figure 1 is a plan view of a collar embodying my invention, the same being laid in a flat position, portions thereof broken away;

40 Figure 2 is a detailed plan view, portions of the collar being broken away and shown in section at one of the reinforced points;

Figure 3 is a transverse sectional view, and

45 Figure 4 is a detailed perspective view showing the manner of forming the reinforcing strips.

In the construction of my improved collar, the same is formed of three separate strips, 1 50 indicating the outer or facing strip and 2 the inner or lining strip, while imposed between these two strips is a stiffening strip 3, said strips being first cut, as indicated in Figure 1, in the shape of collar which is to 55 be formed from the three different strips. The strip 3 when cut will be substantially

longer than the strips 1 and 2, and formed at intervals within this strip are a plurality of box plaits which form transverse stiffening members when the strip 3 is sewed within the collar or between the strips 1 and 2 as shown in Figure 1.

The box plaits formed in the strip 3 are made by folding portions of the strip 3, at intervals, in opposite directions as shown in 65 Figure 4, thus forming opposed folds 4 and 5, which are stitched or otherwise secured together as shown in Figs. 2 and 4. It will be noted that when the strip 3 is folded at intervals in opposite directions, as shown in 70 Figure 4, it provides two sets of opposed folds, one set being folded toward each other and generally indicated at 4 and 5, while the other set of folds are folded away from each other and indicated by the numerals 6 and 75 7 so that when the folds are pressed down tightly together, they form three layers of thickness at this particular point and as these box plaits may be distributed throughout the length of the collar, as shown in 80 Figure 1, they will tend to retain the collar in an upright position and prevent the same from becoming wrinkled or folded transversely of the collar.

In forming the collar after the strips have 85 been cut to the proper length and shape, the box plaits are first formed within the strip 3 and the strip 3 placed between strips 1 and 2 and all three strips stitched together around the outer edges by a double 90 row of stitching, as shown at 8. The collar is then formed in its flattened condition, as shown in Figure 1. In order to form the proper shape of fold collar, the outer portion of the collar which is generally indicated by the numeral 9, is folded on to the neck portion 10 on the line 11 and in order to provide additional stiffening means to the neck portion 10 of the collar, a plurality of rows of stitching 12 are added to the 100 neck portion of the collar to assure the proper fitting of the collar and also to assist in retaining the stiffening plaits in their proper relative positions. In fastening the three strips of material together, the edges 105 of the strip 3 are folded upon themselves and the edges of the lining or inner facing strip are folded over the folded edges of the inner strip 3. The edges of the outer or facing strip 1 are then folded upon themselves and all three folded edges stitched together as shown in Figure 3, thus posi-

tively assuring the connection of all three strips around the entire outer edges.

From the above description taken in connection with the accompanying drawings, it will be readily apparent that I have provided a soft fold collar wherein the stiffening or inner strip is provided with box plaits, said plaits extending transversely entirely across the full width of the collar including both the neck band and the upright portion 9, and it will be noted that by extending the plaits across both the neck band and the upright collar portion, they will securely retain the collar in an upright position and thus eliminate wrinkling and folding of the collar when in position upon the neck of the wearer, three thicknesses of material are provided at each one of the plaits and as the plaits may be arranged any suitable distance apart throughout the length of the collar, it will provide sufficient reinforcement for the same. I wish to call attention to the fact that all three of the strips, indicated at 1, 2 and 3, are the same width throughout the entire length of the collar so that when the collar is folded upon the line 11, the plaits will also be folded upon themselves forming a double

support for the collar at the point where the plaits are arranged.

30

What I claim is:

1. A collar comprising three strips of material sewed together around their edges and the intermediate strip being provided at intervals with reinforcing plaits.

35

2. A collar comprising three strips of material sewed together around their edges, the intermediate strip having reinforced plaits extending transversely thereof, said plaits comprising two sets of oppositely disposed folds and one set of said folds being sewed together at their meeting edges.

40

3. A collar comprising three strips of material, consisting of a facing strip, a lining strip and an intermediate strip interposed between said facing and lining strips, a plurality of rows of stitching connecting said strips, box plaits formed in the intermediate strip and extending transversely across the entire width thereof, said plaits comprising opposed folds formed in the intermediate strip and having certain of the folds connected together along their meeting edges.

45

In testimony whereof I affix my signature.

NATHAN KOBRE.
